UNITED STATES PATENT OFFICE.

WILLIAM H. CLOPTON, JR., OF CAMP MEADE, MARYLAND.

WRENCH.

Application filed September 18, 1919. Serial No. 324,500.

To all whom it may concern:

Be it known that I, WILLIAM H. CLOPTON, Jr., an officer of the United States Army, and a citizen of the United States, residing 5 temporarily at Camp Meade, in the county of Anne Arundel and State of Maryland, have invented new and useful Improvements in Wrenches, of which the following is a specification.

10 The present invention relates to improvements in wrenches and has for its principal object to provide a structure which will permit of slight separation of the jaws while adjusting the tool from one operative position to another, without being disengaged from the member to which it is applied.

In the accompanying drawings,—

Figure 1 is an elevation of a wrench constructed in accordance with the present invention.

20 Fig. 2 is an edge view of the same.

Fig. 3 is a view partly in section showing the jaws in a different relation from that illustrated in Figs. 1 and 2.

25 Fig. 4 is a sectional view on the line 4—4 of Fig. 1.

Figs. 5 and 6 are sectional views on the lines 5—5 and 6—6 of Fig. 1, respectively.

Referring to the drawings, the improved 30 tool comprises a body or handle portion including a U-shaped frame 1, to opposite sides of which are secured plates 2. A relatively fixed jaw 3 is formed at the outer end of a shank or stem 4 that extends between the 35 limbs of the U-shaped body 1 and is provided at its inner end with an interiorly threaded socket 5. An adjusting screw 6, fitted to the body 1, and provided at one end with a knurled head or enlarged portion 7, cooperates with the thread in the socket 5 to adjust the shank or stem 4 and fixed 40 jaw 3 relative to the body or handle, and thus adapt the tool for engaging articles of different sizes.

45 A lever, shown as comprising side members 8 and a connecting section 9, is pivotally connected with one of the members of the U-shaped frame of the body as at 10. The side members 8 of this lever cross opposite faces of the frame of the handle and the shank or stem 4, and each of them is provided with a curved portion 11 that serves as a seat or bearing for the relatively 50 movable jaw 12 of the implement. This 55 movable jaw has a slot through which the shank or stem 4 of the fixed jaw extends

freely and, therefore, when the lever is rocked about its pivot away from the handle, said movable jaw is free to move slightly relative to the fixed jaw, or from the position shown in Fig. 1 to that represented in Fig. 3. By this arrangement, it will be seen that after the jaws have been properly adjusted to engage opposite flat surfaces of a nut 13, for example, it is possible, by positioning the lever as shown in Fig. 3, to enable the jaws to pass the wider portions of the nut, separating adjacent flat surfaces. That is, the wrench may be manipulated in a ratchet-like manner from a position engaging one pair or set of diametrically opposite flat surfaces to a position engaging another set or pair of such surfaces without being disengaged from the nut.

A leaf spring 14 is arranged within the 60 hollow lever, said spring being permanently attached to the frame 1 of the handle or body of the tool and having its free end bearing against the rear wall 9 of the lever. Said 65 spring acts to normally retain the lever in the position shown in Fig. 3, but when it is grasped by the hand, it will be moved into the position shown in Fig. 1, when the two 70 jaws will be properly spaced to grasp the faces of the nut to be turned. To permit 75 of the movement of the jaw 12 relative to the fixed jaw and shank or stem 4 hereinbefore referred to, a portion of the frame 1 is cut away, as at 15. The lever is also preferably 80 provided with a projecting shoulder 16 which will cooperate with the movable 85 jaw to positively move it relative to the fixed 90 jaw in the manner and for the purpose referred to, and thus insure the desired opening 95 of the jaws.

It will be seen that all of the parts of the 100 tool may be made of metal; that the spring for moving the lever in one direction is entirely covered and protected thereby, and that an economical number of parts not likely to be readily disarranged or broken is provided.

Having thus described the invention, what 105 is claimed is:

A wrench comprising a handle having 110 therein a socket that opens through one end, a relatively fixed jaw having a shank or stem extending into said socket and adjustable longitudinally therein, a lever having spaced side members embracing the handle and pivotally connected thereto in rear of the stem of the fixed jaw, adjacent the outer

end of the socket in the handle, the side members of the lever extending beyond the front edge of said stem and provided in their edges with jaw receiving seats, a movable jaw supported in said seats and embracing the stem of the fixed jaw, the movable jaw being situated entirely in planes on the opposite side of the plane of the pivot

between the handle and lever from the fixed jaw, and a spring arranged between the handle and lever and acting to turn the latter to carry the movable jaw away from the fixed jaw. 10

In testimony whereof I have hereunto set my hand.

WILLIAM H. CLOPTON, JR.
